DESIGN FOR A LACE TABLECLOTH

Ferdinand P. Otto, Philadelphia, Pa., assignor to Quaker Lace Company Incorporated, Philadelphia, Pa.

Application March 14, 1941, Serial No. 99,667

Term of patent 3½ years

To all whom it may concern:

Be it known that Ferdinand P. Otto, a citizen of the United States of America, residing at 6903 North 20th Street, Philadelphia, in the county of Philadelphia and State of Pennsylvania, has invented a new, original, and ornamental Design for a Lace Tablecloth, of which the following is a specification, reference being had to the accompanying drawing, forming a part thereof, in which the figure is a face view of a quarter section of the lace cloth showing my new design, the other three sections being identical with that here disclosed, arranged in proper relation to complete the lace tablecloth. The quarter section of the cloth is shown over a dark background to bring out the details of the lace design.

I claim:

The ornamental design for a lace tablecloth, substantially as shown and described.

FERDINAND P. OTTO.
